DESIGN FOR A HAT

Samuel Finkelstein, New York, N. Y.

Application January 11, 1938, Serial No. 74,207

Term of patent 3½ years

To all whom it may concern:

Be it known that I, Samuel Finkelstein, a citizen of the United States and residing in Manhattan, in the city, county, and State of New York, have invented a new, original and ornamental Design for a Hat, of which the following is a specification, reference being had to the accompanying drawing, forming part thereof,

Fig. 1 is a perspective view of the hat.

Fig. 2 is a side elevational view of the ornament on the top of the hat shown in Fig. 1.

Fig. 3 is a bottom plan view of Fig. 2.

The characteristic feature of my design resides in the button applied to the top of the hat.

The shaded portions represent a contrasting color.

I claim:

The ornamental design for a hat substantially as shown and described.

SAMUEL FINKELSTEIN.
